UNITED STATES PATENT OFFICE.

FRANK WIBERLEY, OF JAMAICA, NEW YORK, ASSIGNOR TO BARTHELS MANUFACTURING COMPANY, OF GLENDALE, NEW YORK, A CORPORATION OF NEW YORK.

DESIGN FOR A TAPE.

55,348.

Specification for Design.

Patented May 25, 1920.

Application filed December 11, 1918. Serial No. 266,347. Term of patent 14 years.

To all whom it may concern:

Be it known that I, FRANK WIBERLEY, a citizen of the United States, residing at Jamaica, in the county of Queens and State of New York, have invented a new, original, and ornamental Design for a Tape, of which the following is a specification, reference being had to the accompanying drawing, forming a part thereof, and in which—

Fig. 2 an edge view of a strip of tape embodying my design.

I claim:

The ornamental design for a tape, as shown.

FRANK WIBERLEY.
